UNITED STATES PATENT OFFICE.

JOEL CONOVER, OF COBLESKILL, NEW YORK, AND FRANK CONRICK, OF DUBUQUE, IOWA.

FIRE-ESCAPE.

SPECIFICATION forming part of Letters Patent No. 375,440, dated December 27, 1887.

Application filed October 19, 1887. Serial No. 252,787. (No model.)

To all whom it may concern:

Be it known that we, JOEL CONOVER, of Cobleskill, in the county of Schoharie and State of New York, and FRANK CONRICK, of the 5 city and county of Dubuque, in the State of Iowa, have invented new and useful Improvements in Fire-Escapes, of which the following is a specification.

Our invention relates to improvements in 10 apparatus for aiding the escape of persons from burning buildings; and the object of our invention is to provide a simple, safe, and effective apparatus for the purpose above named, and to render the apparatus reversible, in order 15 that it may be used either side uppermost. This object we attain by the construction illustrated in the accompanying drawings, which are herein referred to and form part of this specification, and in which—

20 Figure 1 is a front elevation of our fire-escape with its clamping-bars locked together. Fig. 2 is a like elevation with the clamping-bars spread apart to permit the suspension-rope to render between them. Fig. 3 is a like 25 elevation of our fire-escape in its reversed position, and Fig. 4 is a transverse section of Fig. 1 at the line X X.

As represented in the drawings, A is the 30 suspension-rope of our fire-escape, which rope is preferably provided at each end with an eye, 1, for the purpose of facilitating the suspension of the apparatus either side uppermost from a stationary hook or other fixed point.

35 B and B' are clamping-bars, which form a grip for sustaining the weight of a person on the suspension-rope A. Said clamping-bars are spaced at such a distance apart that the opening between the adjacent edges of the two 40 will be sufficiently less than the diameter of the suspension-rope A to produce a grip on said rope that will normally prevent it from rendering when said bars are locked together by any simple device that will not create confusion or delay in case of emergency or when the suspended weight is equally borne on both of said bars. Said clamping-bars are pivoted together by means of a strap-joint, C, so as to swing toward and from each other on the 45 pivotal center 2.

The suspension-rope A is preferably in-

serted in the upper edge of the bar B and passes out at the side of the same. It is then rove crosswise between the adjacent edges of the bars B and B', then into the side of the 55 latter, and preferably out at the bottom of the same. Said rope is then preferably carried over the upper edge of the bar B' at a point at the opposite side of the pivotal center 2, and in passing transversely over the upper 60 edge of the bar B' said rope passes through a staple, 3, which prevents it from slipping out of place. The lower part of said rope hangs pendent from the clamping-bars.

D is a safety-band that is intended to be 65 passed around the chest, under the armpits, of a person who is about to descend on the apparatus. Said safety-band should be provided with a sliding loop, 4, for the purpose of adjusting the bight of said band to the 70 person. When said safety-band is required to be detachable, which is our preferred construction, it is provided at each end with a snap-hook, 5, or other appliance for quickly 75 attaching and detaching it from the clamping-bars when occasion requires. One end of the bar B' is provided with a becket, E, which has an eye, 6, at each end. Said becket is secured to the bar B', so that it will not slip therein, and so that one end of the safety-belt 80 D can be engaged in either of the eyes 6 that occasion may require. At the opposite end of the bar B' a hand-rope, F, is secured, so that it will not slip. The fastened end of said hand-rope is provided with a hand-loop, 7, or 85 other appliance, to which a pull of the hand can be applied. The other part of said hand-rope, after being rove first up and then down through the bar B, and then down through the bar B', is provided with an eye, 8, to which 90 an end of the safety-band D engages to complete the attachment of the latter to the clamping-bars.

Our fire-escape operates in the following manner: The suspension-rope A being attached by one of its eyes 1 to a hook, 9, or other secure fastening that is adjacently located to a window or other opening of a building, and the safety-band D, with its sliding loop 4, arranged to give ample size to the bight 95 of said band for slipping over the shoulders of a person, being attached to the clamping-bars.

The bight of the safety-band is fixed around the chest of the person that is about to descend, and the sliding loop is adjusted to bring the bight of the safety-band snugly around the person. The latter slips out of the window with his weight sustained by the suspension-rope A, which is gripped by the clamping-bars, so that it cannot render through the latter. The weight will then be equally distributed at both ends of the clamping-bars, so that the latter will operate as a brake to prevent the descent of the person until he is ready to do so. Then a strain is applied to the hand-rope F, that will suffice to draw down the corresponding end of the bar B' and effect a release of the grip of the clamping-bars on the suspension-rope A, whereupon the latter will freely render through said clamping-bars and permit the latter and their attached load to slide easily downward. If, during excitement, too great a strain is applied to the hand-rope F, the end of the bar B' to which said hand-rope is attached will be drawn down to such a degree that its opposite end will grip that part of the suspension-rope A which passes through the staple 3, and thereby the clamping-bars will be brought into action to operate as a brake on that part of the rope A last referred to, and thereby the descent of the suspended load will be entirely stopped or its speed will be checked until the strain is partially removed from the hand-rope. By entirely removing the strain from the hand-rope F the grip of the clamping-bars near their middle can be reapplyed to the suspension-rope A, and the descent of the load will be thereby stopped.

When the person on the fire-escape has reached the ground and the apparatus is required for saving others from the same apartment, it can be raised by means of the part of the rope that is uppermost, and after being raised and its position reversed, as shown in Fig. 3, it is ready for an immediate repetition of the operation just described. When preferred, the safety-band D may be permanently attached to the apparatus; but in the latter case the apparatus will not be reversible.

It is obvious that our fire-escape can be used without passing a part of the rope A through the staple 3, and a satisfactory result thereby attained; but, as a more perfect control of the apparatus can be had by the arrangement first described, we prefer to retain it in its entirety.

We claim as our invention—

1. In a fire-escape, the combination of a pair of clamping-bars that are pivoted together to swing toward and from each other in a vertical plane, a suspension-rope that passes through the body of both clamping-bars and transversely between them, so that said clamping-bars will operate as a grip on said rope, and a safety-band attached to said clamping-bars, as and for the purpose herein specified. 55
2. A reversible fire-escape comprising a suspension-rope, A, a pair of clamping-bars, B and B', that are pivoted together, as at 2, to swing toward and from each other in a vertical plane, the bar B' being provided at one end with a becket, E, having an eye, 6, at each end, 60 the opposite end of said bar having secured thereto a hand-rope, F, which has at one end a hand-loop, 7, and at the opposite end an eye, 8, said hand-rope being rove through one end of both clamping-bars to operate as described, 70 and a safety-band, D, provided with hooks or other fastenings for connecting said band with said clamping-bars, as and for the purpose herein specified. 75
3. In a fire-escape, the combination of a pair of clamping-bars and a reversible suspension-rope, said clamping-bars being pivoted together to swing toward and from each other in a vertical plane, and the said suspension-rope being rove through the body of both 80 clamping-bars and passed transversely between said bars at each side of their pivotal center, as and for the purpose herein specified. 85
